UNITED STATES PATENT OFFICE.

LÉON LEBLANC, OF RUTLAND, VERMONT.

CENTRIFUGAL PUMP.

SPECIFICATION forming part of Letters Patent No. 718,642, dated January 20, 1903.

Application filed December 17, 1901. Serial No. 86,289. (No model.)

To all whom it may concern:

Be it known that I, LÉON LEBLANC, a citizen of the United States, residing at Rutland, in the county of Rutland and State of Vermont, have invented certain new and useful Improvements in Centrifugal Pumps; and I do hereby declare the following to be a full, clear, and exact description of the invention, such as will enable others skilled in the art to 5 which it appertains to make and use the same.

My invention relates to improvements in rotary or centrifugal pumps.

The objects of the invention are to effect facility of operation or action, to dispense 15 with all packing and hand lubrication, to render the working parts self-lubricating, to reduce friction or wear and tear, to simplify construction, to promote durability, to provide for interchangeability of mechanism, and 20 to otherwise add to the practicability and utility of the pump.

It consists of the sundry combination of parts, including their construction and arrangement, substantially as hereinafter more 25 fully disclosed, and specifically pointed out by the claims.

In the accompanying drawings, forming part of this specification and illustrating the preferred embodiment of my invention, Figure 1 is a plan view thereof. Fig. 2 is a sectional elevation taken on the line xx of Fig. 1. Fig. 3 is also a sectional elevation at right angles to the section-plane of Fig. 2, taken on the line yy of Fig. 1. Fig. 4 is a section 30 taken on the line zz of Fig. 3. Fig. 5 is a plan view of the piston removed from its containing-chamber. Fig. 6 is a modified form of bracket for the piston stem or rod. Fig. 7 is a broken section taken on the dotted line 40 of Fig. 4.

Latitude is allowed herein as to details, as they may be changed according to circumstances without departing from the spirit of my invention and the same yet remain intact 45 and be protected.

In carrying out my invention I arrange within a suitable closure or casing 1, in the lower part thereof, preferably a separate closure or chamber 2, comprising two horizontally-separable parts or sections 2^a 2^b suitably connected together, being preferably produced at diagonally-opposite corners with

registering openings to receive and permit the passage therethrough of nutted rods 7, with their lower ends screwed into the bottom of the casing 1. In the meeting surfaces of said chamber-sections at or near one corner are produced, preferably, short concaved channels, jointly forming the water-discharge passage or port 8, and with said port preferably communicates a delivery-pipe 9, screwed into the casing 1. The piston 5, being in its general construction cylindric, has its stem or rod 5^a preferably screwed into the threaded walls of a central opening 5^b , extending 55 through a central part or disk of said piston. Said stem or rod itself has its lower end bored to a suitable depth, as at 5^c , to receive a "step" or support 3, preferably secured centrally in the bottom of the casing or closure 60 1 and passing through the bottom of the piston-chamber 2. Said step has in its upper end a concavity or depression to receive a spherical or ball bearing 3^a , engaging the concaved seat 5^e , formed by the upper end 70 of the bore 5^c in the lower end of the piston or stem 5^a , said seat having a preferably hardened surface. Said piston rod or stem is equipped with a pulley 5^d , adapted to be engaged or driven by a suitable belt (not 75 shown) as one form of actuating the piston. Said piston 5 has, as above noted, a central disk-like part 5^x , preferably beveled more or less upon its upper and lower surfaces or edges at the periphery. Between said central disk-like part and the top and bottom portions 5^e 5^f , respectively, of said piston are produced radial arms or partitions 5^{xx} , preferably cast integral with said central part. Said arms or partitions 5^{xx} increase in their 80 horizontal surfaces or areas from the inner edges or ends outwardly toward and coincide at their outer edges with the peripheral outline of the piston. The butt or rear edge or surface of each arm or partition partially extends in a radial line with relation to the center or rod of the piston and partially tangentially to said center or rod or at an angle to the radial portion at less than a right angle. The front edge or surface of each arm extends 95 100 from a point removed a short distance from said rod or center straight outwardly parallel with the radial or straight portion of the rear edge of the opposite arm and then curves

or extends in a corresponding or coincident angle with the angular edge of said rear edge of the opposite arm. Thus a plurality or number of corresponding water ways or passages 5 6 are formed by and between each series of said arms, the function of which will presently appear. The top and bottom portions 5^e 5^f of said piston have each a preferably circular opening or orifice 5^e 5^h centrally there-
: 10 through, respectively. The opening or orifice 5^g effects communication between the upper water-chamber of the casing or closure 1 and the upper series of water ways or passages of the piston via a central corresponding opening 5^{bb} in the top of the piston-chamber 2 for actuating or driving said piston, the function of the opening or orifice 5^h being hereinafter disclosed. The under side of the top of the piston-chamber 2 has depending therefrom 15 around the orifice or opening 5^{bb} a circular flange or guard 5ⁱ to prevent the water flowing or being forced back through said orifice in event of any obstruction occurring in the pump. Also the upper surface of said piston-chamber top is preferably dished or con-
20 caved centrally, as at 5^{ab}, to drain or conduct the water in the upper or water chamber of the casing or closure 1 to and through the central orifice 5^{bb} in delivering the water to 25 the upper series of piston water-passages.
30

In the upper surface of the bottom of the casing or closure 1 is a water chamber or passage 4, extending, preferably, diagonally therein from near the step or support 3 toward and stopping adjacently to one corner of said closure or casing. The bottom of the piston-chamber 2 has an opening or orifice 4^a therethrough, coinciding with the inlet end of said passage or channel, and to the 35 inner surface of the bottom of said piston-chamber is secured a circular upstanding flange or guard 4^x, with its upper end or edge entering the orifice or opening 5^h of the piston contiguously to its shaft-supporting step 40 3, the function of which will be presently disclosed. Communicating with the opposite end of the chamber or passage 4 is a vertical passage 4^b, (see particularly Fig. 7,) with a pipe-section 4^c preferably screwed into its 45 upper end and forming an upward continuation or extension thereof. The upper end of said pipe-section may stop near the water-level in the water-chamber of the casing or closure 1 or even extend thereabove for passing 50 or delivering water into the channel or passage 4, the extension of said pipe-section being adapted should it be desired to pass air into the latter in lieu of water.
55

It will be observed that by passing water 60 from the water-chamber of the casing or closure 1 into and through the pipe-section 4^c, the chamber or passage 4, and via the parts 4^a 4^x, and 5^h into the piston-chamber it will be delivered around the piston-shaft step 3, 65 the same passing also up into the socket or bore 5^{cc} and surrounding the bearing of said shaft. This will have the effect, it is be-

lieved, to lubricate the parts or bearing as well as cushion, by the buoyant action of the water, the same, thus dispensing with all 70 packing and the usual form of lubrication which may be used at this time for that purpose. Also it is further observed that the sedimentary portion of the water, including gritty substances, gravel, &c., settling toward 75 the bottom of said water-chamber and naturally passing to the upper series of piston buckets or passages, the upper portion of the water will be practically free of all such objectionable or injurious substances and will 80 therefore be permitted to be delivered accordingly to said shaft-bearing and other parts in the manner above pointed out, thus be unattended with the otherwise impairing or premature wearing action thereon. This 85 water passing via the lower series of piston buckets or water-passages to the piston-shaft bearing, &c., is carried out by the centrifugal action generated by the movement of the former and discharged with the discharged 90 water from the upper series of piston buckets or passages, as is apparent.

Arranged removably and adjustably contiguously to the channels forming the discharge-port 8, in suitable recesses produced 95 in the piston-chamber sections, is a hard wear-piece 10. Said hard-metal wear-piece as it wears away more or less from frictional contact with the periphery or face of the piston when the latter is in action is moved or adjusted inwardly to compensate such wear by manipulation of the adjusting-screw 10^a. Said delivery-pipe 9 has an intermediate discharging valved pipe 11, adapted to overhang and discharge into a supplemental chamber 105 or receptacle 12, fixed to and having its upper edge a short distance above the casing or closure. Communication between said casing or closure 1 and the receptacle is preferably effected through a valved opening 13 110 for delivering water, &c., into said casing—for instance, when starting the pumping operation also for holding water, &c., back when the pump is not in operation. The valve 11^a in the pipe 11 is designed more particularly for effecting the discharge and keeping everything out of the pump when its operation is stopped. This is effected after first closing the valve 14, presently described, by opening the valve 11^a and blowing out the 120 remaining contents of the pump via the pipe 9 and pipe 11, the latter discharging such contents into the receptacle 12. The valve 14 for closing the orifice or opening 13 of the receptacle or chamber 12, which valve is opened 125 when it is desired to deliver the contents of said receptacle into the pump-casing, preferably comprises a horizontal handled rod or shaft 14^a, axially supported in suitable bearings 14^b, secured to the side of the receptacle 12 next to the casing 1, and the valve proper, 14^c, preferably a plate rigidly secured to said rod between its bearings and having secured thereto a disk of leather or the like, as will

be readily understood, is adapted to cover or close the opening or orifice 13.

A suitable bracket or casing 15 with a horizontal angular foot or base 15^a, suitably secured or bolted to the top edge of the receptacle 12, has spaced-apart tubular extensions or arms 15^b to receive and steady the stem or rod 5^a of the piston 5, as when driven by a belt and the pulley 5^a, above referred to.

As shown in Fig. 6, I may employ in lieu of the aforesaid bracket a bracket 16 in case it should be desired to drive the piston from a horizontal shaft. Said bracket preferably comprises a tubular bearing 16^a, adapted to receive the upper end of the piston stem or rod and to house or inclose a beveled pinion or gear applied to said stem or rod and a second similar bearing 16^b, adapted to receive a horizontal shaft, and a tubular housing or closure 16^c, arranged diagonally or in an inclination between and integral with the bearings 16^a 16^b to inclose or house an intermediate shaft and beveled gearing on said horizontal shaft and said intermediate shaft, as will be readily understood.

Having thus described my invention, what I claim as new, and desire to secure by Letters Patent, is—

1. In a centrifugal or rotary pump, an impeller having two series of water passages or buckets, with its shaft-bearing, a casing or closure having an upper water-chamber and a lower chamber containing said impeller, said upper chamber initially wholly receiving the water passing through said buckets or passages, and means for conducting that portion of said water freed of sediment or gritty substances laterally of said lower chamber and delivering it up through the bottom of the last-named chamber, past said shaft-bearing, to the lower series of water passages or buckets of said impeller.

2. In a centrifugal rotary pump, the combination with a casing or closure, having an upper chamber and a lower chamber, and a piston, with a shaft-bearing, comprising a central partition or disk, equipped with a plurality of spaced-apart arms, with an upper and lower series of water passages or ways therebetween, the upper ones of which series of waterways communicating with the upper one of said chambers, and the lower ones of which series of waterways communicating with a corresponding chamber, said upper water-chamber adapted to initially receive the whole of the water passing through the piston-buckets and to deliver that portion of said water freed of sediment or gritty substances, via, said lower chamber, past said shaft-bearing, to the lower series of piston-buckets, said arm having outwardly-enlarging portions, alining the peripheral outline of the piston, with the butt or rear end of each arm adapted to partially stand radial to the center of the piston and partially tangential to said center, and the face or front portion of each arm extending in a straight line from a

point near said center and parallel with a rear radial edge of the opposite arm and curved or extended in a corresponding angle 70 with the angular edge portion of said opposite arm.

3. In a rotary pump, a closure or casing having an upper chamber and a lower chamber, and a water-passage arranged in the upper or 75 inner surface of said lower chamber, a piston with its shaft-bearing, having an upper series, and a lower series, of water-passages and an orifice communicating with the first-named passage, said passage communicating with 80 said upper chamber.

4. In a rotary pump, a casing or closure having an upper chamber, a lower chamber, and a water-lubricating passage in the inner surface of its bottom, a piston, with its shaft- 85 bearing, having an upper series, and a lower series, of water-passages and an orifice communicating with said passages and a tube or pipe section arranged in the said piston-chamber and communicating with said passage and 90 said upper chamber.

5. In a rotary pump, a casing or closure having an upper chamber, and a lower chamber, and a delivery or discharge orifice or outlet, one of said chambers having a discharge-port, 95 and a piston, with its shaft-bearing, having two series of radial water ways or passages, with the walls or arms therebetween having their rear or butt edges partially radial and partially tangentially to the center of said piston, and 100 their front edges or faces partially straight and partially extended in lines corresponding with said rear edges, said upper chamber having a passage connection with the lower series of water-passages of said piston. 105

6. In a rotary pump, a casing or closure having an upper chamber, and a lower chamber, a piston, with its shaft-bearing, having a central or subdividing portion, with two series of spaced-apart arms therebetween and the top 110 and bottom of said piston, forming water ways or passages, the lower ones of which communicate with said upper chamber via, a passage opening up from the bottom of said lower chamber. 115

7. In a rotary pump, a casing or closure having an upper chamber, and a lower chamber, a piston, with its shaft-bearing, having a central or subdividing portion, with two series of spaced-apart arms therebetween and the top 120 and bottom of said piston, forming water ways or passages, the lower ones of which communicate with said upper chamber, via, a passage opening up from the bottom of said lower chamber, said arms having their rear edges 125 partially radial and partially tangential to the center of said piston and their front edges or faces partially straight and partially extended in lines corresponding with said rear edges. 130

8. In a rotary pump, a casing or closure having an upper chamber and a lower chamber, a piston, with its shaft-bearing, having a central or subdividing portion beveled near its

- peripheral edge and having integral therewith two series of arms forming a series of water ways or passages, the lower ones of which communicate with said upper chamber, via, 5 a passage opening up from the bottom of said lower chamber, said arms having their rear edges partially radial partially tangential to the center of said piston, and their front edges or faces partially straight and partially ex- 10 tended in lines corresponding with said rear edges, and a piston-chamber having an upper chamber and a lower chamber and its upper or top portion provided around its central opening with an inner or depending flange 15 or guard concentric of the waterways of said piston, the lower water-passage communicat- ing with said upper chamber via, a passage opening up from the bottom of said piston- chamber.
- 20 9. In a rotary pump, a casing or closure having an upper chamber, and a lower chamber, and the centrifugal piston arranged in said lower chamber, said piston-chamber having a central opening or orifice therein, an inner 25 depending flange concentric of the water ways or passages of said piston, the lower wa- ter-passage communicating with said upper chamber, via, the passage opening up from the bottom of said piston-chamber.
- 30 10. In a rotary pump, a casing or closure for the piston having a delivery-pipe provided with a valved intermediate pipe and a sup- plemental chamber or receptacle arranged to receive the water from said intermediate pipe, 35 substantially as set forth.
11. In a rotary pump, a casing or closure for the piston, having a delivery-pipe provided with a valved intermediate pipe, a supple- 40 mental chamber or receptacle having a valved opening adapted to deliver into said casing or closure, said supplemental chamber adapted
- to receive the water from said intermediate pipe, substantially as set forth.
12. In a centrifugal or rotary pump, a ro- 45 tary piston having two series of water pas- sages or buckets, with its shaft-bearing, and a casing or closure having an upper water- chamber and a lower chamber containing said piston, said upper water-chamber adapted to deliver its contents, via said lower chamber 50 into the lower series of buckets, and a pas- sage leading from said upper chamber, and opening up through the bottom of said lower chamber and into the piston, around its shaft- bearing, said upper chamber also adapted to 55 deliver into the upper series of water pas- sages or buckets of said piston, substantially as set forth.
13. In a centrifugal or rotary pump, a ro- 60 tary piston having two series of water pas- sages or buckets, with its shaft-bearing and a casing or closure having an upper water- chamber and a lower chamber containing said piston, said upper water-chamber adapted to deliver its contents, via said lower chamber 65 into the lower series of buckets, and a pas- sage leading from said upper chamber, and opening up through the bottom of said lower chamber and into the piston, around its shaft- bearing, said upper chamber also adapted to 70 deliver into the upper series of water pas- sages or buckets of said piston, and said shaft- bearing comprising a "step" or support en- tering a socket or bore in the lower end of the piston-shaft, substantially as set forth. 75

In testimony whereof I affix my signature in presence of two witnesses.
